UNITED STATES PATENT OFFICE.

FLORIO SEPERAK, OF LEAD, SOUTH DAKOTA.

METHOD OF SPLICING WIRE CABLES.

No. 856,493.

Specification of Letters Patent.

Patented June 11, 1907.

Application filed October 22, 1906. Serial No. 340,043.

To all whom it may concern:

Be it known that I, FLORIO SEPERAK, a citizen of the United States, residing at Lead, in the county of Lawrence and State of South Dakota, have invented a new and useful Method of Splicing Wire Cables, of which the following is a specification.

This invention relates to a method of splicing flat wire cables.

In mining it is common to use what is known as a flat wire cable for hoisting and similar purposes. These cables are formed by stitching together a number of round wire cables, each round wire cable being formed of four strands and being twisted alternately right and left hand, thus, for instance the round wire cable at the edge may have a right hand twist, the second a left hand twist, the third a right hand twist, and so on throughout the width of the flat wire cable. Each strand of each cable is formed of a center or core wire and six outside wires, and the wires of each strand are twisted together in a direction the opposite of that in which the several strands are twisted together to form a cable.

In case of breakage or where a cable is lengthened by splicing on another section, it is found extremely difficult to form a splice which will not increase the cross sectional area of the cable at any point, owing to the fact that the round wire cables are in parallel relation instead of being twisted to form a round cable as usual, and at the splicing point the various parts which go to make up the entire cable cannot be interlaced in the same manner as they are in a cable circular in cross section.

These and other difficulties are overcome by the improved method of splicing flat wire cables, hereinafter described and claimed.

In the accompanying drawings:—Figure 1 is a view of a portion of the flat wire cable indicating the points at which the splice has been made. Fig. 2 is a transverse sectional view through a portion of the cable showing the method of sewing the cable together flatwise. Fig. 3 is a detail perspective view of one of the strands showing the method of splicing the wires of which the strand is formed.

The flat wire cable is formed of a number of round wire cables, four of which, designated generally 1, 2, 3 and 4, are shown in the present instance, and each of these round

wire cables is formed of four strands 5 without any center core. The strands of cables numbered 1 and 3 have a right hand twist, and the strands of cables 2 and 4 have a left hand twist, and after all of the cables are laid together side by side they are stitched together by cross wires 6 which may be formed of a strand opened out, or a number of wires arranged together in parallel relation in any suitable manner. The sewing strand 65 is passed directly across the cables, two strands on each cable being above the sewing strand, and the remaining two strands of each cable being below said sewing strand. Where the sewing strand is brought to the outer edge of the flat cable, it is carried along a short distance, and after passing over one of the strands of the edge cable, is again forced through the entire series of round cables, as clearly shown in Fig. 1.

Where the cable has been broken, or it is desired to lengthen the same, the sewing strands are severed in order that the several round cables may be opened out for a considerable distance. The four strands of each wire cable are also untwisted, and opened out, and then the seven wires of each strand are opened out. The wires of each strand are then cut to different lengths, after which the ends of the main cable 6 to be united are brought together, and the splicing proceeds. The seven wires of each strand of one section of the cable are separately spliced to the seven wires of each strand of the other section, the splicing points or terminals of the wires being arranged at different points, respectively, in the lengths of the strands, so that the splicing is distributed over a very large area, and there can be no undue increase in the cross sectional area of the cable at any one point.

The splicing of each strand is carried on in the manner familiarly known as long splicing, wherein the ends of the wires are cut different lengths after laying back, and the shortest wire of one strand is brought adjacent to the longest wire of the other strand, and the ends after crossing are tucked under adjacent wires, so that they may be firmly held when tensional strain is exerted on the cable. After all of the individual strand have been spliced together, the strands of each of the round cables are twisted together and then the round cables are united by the sewing or stitching wires in order that

they may be held out in the form of a flat cable.

I claim:—

That method of splicing flat wire cables which consists in opening out the several round cables of which the cable is formed, separating the strands of each round cable, opening the wires of which each strand is composed, and connecting the wires of meeting strands by long splicing at such points that no two splices are in line transversely of

the cable, twisting the strands to form the round cables, and then sewing the round cables together.

In testimony that I claim the foregoing as my own, I have hereto affixed my signature in the presence of two witnesses.

FLORIO SEPERAK.
